UNITED STATES PATENT OFFICE.

WILLIAM J. ANDERSON, OF MENANDS, NEW YORK.

CONCRETE-CONSTRUCTION FORM-BRACE.

1,101,382.

Specification of Letters Patent. Patented June 23, 1914.

Application filed May 21, 1913. Serial No. 769,055.

To all whom it may concern:

Be it known that I, WILLIAM J. ANDERSON, a citizen of the United States, residing at Menands, in the county of Albany and State of New York, have invented new and useful Improvements in Concrete-Construction Form-Braces, of which the following is a specification.

The invention relates to form braces for concrete construction, and more particularly to the class of adjustable form braces for constructing culverts, conduits, bridges or the like from concrete or other cementitious material.

The primary object of the invention is the provision of a form brace in which the parallel longitudinal bars are connected together through the medium of transverse or cross links which are pivoted thereto so that the form brace can be readily and easily adjusted as regards its height and width and also with respect to the length, thereby enabling the same to be used for constructing culverts, conduits, bridges or the like of concrete or from other composition matter.

Another object of the invention is the provision of a form brace wherein the same can be worked to vary the cross section thereof and held rigid in such adjusted position, the construction of the brace being devoid of complicated mechanical parts which would necessarily require skilled labor to operate.

A further object of the invention is the provision of a form brace in which the frame-work can readily and easily be put in position for use and also which can be removed without any great loss of time, thereby affording a convenient device for use in the building of concrete structures.

A still further object of the invention is the provision of a form brace which is simple in construction, readily and easily adjusted, strong, durable, thoroughly reliable and efficient in its operation, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawings: Figure 1 is a side elevation of a form brace constructed in accordance with the invention. Fig. 2 is a top plan view thereof. Fig. 3 is an end elevation. Fig. 4 is a sectional view on the line

4—4 of Fig. 1. Fig. 5 is a fragmentary side elevation of the form brace in adjusted position. Fig. 6 is a vertical longitudinal sectional view through the brace.

Similar reference characters indicate corresponding parts throughout the several views in the drawings.

Referring to the drawings by numerals, the form brace comprises a plurality of longitudinal bars 10, each being made from L-shaped iron in cross section, of the required length. Connected at intervals to the flanges of the bars 10 are transversely disposed short bars or links 11 which have their ends engaged with pivots 12 mounted in the said bars 11 so that the bars or links 11 will swing in unison angularly with respect to the bars 10, the latter being held parallel with each other through the medium of the bars or links 11 when being shifted so that the brace form may be readily and conveniently adjusted to vary the cross sectional area thereof, which is uniform throughout its extent. Interposed between the flanges of the bars 10 and the ends of the bars or links 11 pivoted thereto are washers 13 which avoid undue friction between the bars when the form brace is being adjusted, the washers being supported in position by means of the pivots 12 which carry the same.

Mounted at one end of the form brace are clamps, preferably four in number, each comprising a frame 14 which is suitably secured to one of the longitudinal bars 10 and has arranged in its open center pivotally connected swinging and stationary jaws 15 and 16 respectively, the stationary jaw being secured by means of rivets 17, while threaded in one end of the frame 14 is a clamping screw 18, the inner end of which works against the swinging jaw 16, and its outer end is formed with a handle 19 so that it may be readily turned for the locking or unlocking of the swinging jaw. The inner edges of the jaws 15 and 16 are formed with convergent beveled working surfaces 20 for engagement with a substantially wedge-shaped anchoring block 21 which is held fast by the jaws 15 and 16 when the said swinging jaw is moved into clamping relation to the stationary jaw, the block 21 being provided with an eye 22 to which is fastened one end of a releasing and adjusting cable 23, there being four of these and each one having its opposite end engaged with the hook member 24 of a turn buckle 25, the

2
 eye member 26 of which being fixed to the opposite end of the form brace. This eye member 26 of the turn buckle 25 is mounted upon one of the longitudinal bars 10 opposite the bar carrying the clamp.

Crossing the stretch of the releasing and adjusting cables 23 are stay cables 27 there being four of the same, and each of which has one end connected to a hook 28 pivoted 10 to the longitudinal bar 10 carrying the eye member 26 of the turn buckle 25, while the opposite end of the said stay cable is connected to the hook member 29 of a turn buckle 30, the eye member 31 of which is 15 mounted on the other end of the longitudinal bar 10 to which the clamp is fastened. The turn buckles 25 and 30 are employed to permit of accurate adjustment of the form brace with regard to height and width. The 20 cable 23 permits the adjustment of the form brace and also the clamp therefor permits the release of the cable so that the said form brace can be collapsed, while the stay cable 27 sustains the form brace adjusted and 25 against collapsing.

The longitudinal bars 10 are each made up of a plurality of sections 32 and 33 respectively, so that the length of the form brace can be varied as the occasion requires. 30 The sections 32 of the bars 10 have fixed thereto joining collars or clips each comprising inner and outer L-shaped plates 34 and 35 which are united to one end of each section 33 by means of rivets, and between 35 these plates are frictionally engaged the ends adjacent thereto of the sections 33 for the joining of the said sections 32 and 33.

Secured at intervals to the longitudinal bars 10 at one side of the form brace are 40 roller sheaves 36 in which are journaled supporting rollers 37, the side of the form brace carrying the rollers being designated as the bottom thereof, and these rollers permit the convenient and easy moving of the 45 form brace into positions for constructing a culvert, conduit, bridge or the like from concrete or other composition material.

In the use of the form brace the same is 50 positioned at the required location and adjusted according to the desired height and width of the opening to be made for the forming of the culvert, conduit, bridge or the like, and thereafter the frame-work forms are positioned about the form brace

exteriorly thereof, the frame-work forms being of the ordinary well-known construction, one example of which is illustrated in Fig. 3 of the drawing. After the frame work forms are positioned the concrete or other composition material is deposited in 60 the usual manner, and when the same has been allowed to set it is necessary to remove the frame-work form and the frame brace from the opening, and this is done by loosening the screws 18, which permit the swinging 65 of the jaws 15 to position for freeing the blocks 21, thereby releasing the releasing and adjusting cables 23 which permits the collapsing of the frame brace so that the frame-work forms can be readily removed 70 from the opening, and thereafter the frame brace is removed, it being understood of course that the stay cables do not have to be released or detached for the collapsing 75 of the frame brace.

From the foregoing it is thought that the construction and manner of operation of the device will be clearly understood, and therefore a more extended explanation has been omitted.

80 What is claimed is:—

1. A form brace comprising an adjustable and collapsible four-sided form structure, each side being adjustable to vary the area 85 thereof, means for sustaining the said sides in adjusted position, and rollers supported by one of the sides.

2. A form brace comprising an adjustable and collapsible four-sided form structure, each side being adjustable to vary the area 90 thereof, means for sustaining the said sides in adjusted position, rollers supported by one of the sides, and means for detaching the adjusting means.

3. A form brace comprising an adjustable 95 and collapsible four-sided form structure, each side being adjustable to vary the area thereof, means for sustaining the said sides in adjusted position, rollers supported by one of the sides, means for detaching the adjusting means, and turn buckles engaged 100 with the said adjusting means.

In testimony whereof I affix my signature in presence of two witnesses.

WILLIAM J. ANDERSON.
